INVENTOR.

Clarence Braden Greenstreet

UNITED STATES PATENT OFFICE.

CLARENCE BRADEN GREENSTREET, OF INGLEWOOD, CALIFORNIA.

AUTOMOBILE LIGHT-BULB CABINET.

Application filed July 24, 1923. Serial No. 653,583.

To all whom it may concern:

Be it known that I, CLARENCE BRADEN GREENSTREET, a citizen of the United States, and a resident of Inglewood, in the county of Los Angeles and State of California, have invented certain new and useful Improvements in an Automobile Light-Bulb Cabinet, of which the following is a specification.

10 The main objects of this invention are to provide an improved method for displaying the different kinds of light bulbs used on automobiles or similar vehicles, to provide an improved and compact arrangement of the several sizes, to provide improved means, for handling, care and storage and to furnish adequate means for quick discrimination in supplying the public need.

20 The invention consists in the details of construction and in the combination and arrangement of the several parts of my improved light bulb cabinet whereby certain important advantages are attained and the design is rendered simpler, less expensive 25 and otherwise more convenient and advantageous for use, all as will be herein-after more fully set forth.

An illustrative embodiment of these essentials is shown in the accompanying drawing in which Fig. 1 represents a perspective view of the cabinet, Fig. 2 a horizontal section taken on line 1—1 and Fig. 3 is a perspective view of spacer. Similar parts are designated by like numerals in the different views.

In the construction shown in the drawing 1 denotes the cabinet or container of any ordinary or preferred construction into which the shaft 6 is fastened at the top and bottom and which is the main axis of support of the movable paddles 2 and 10 which are provided with a plurality of holes 4 and 11 to be used as receptacles for the different kinds and sizes of light bulbs.

45 To the cabinet 1 is framed the door 7 having a transparent glass 12 swinging on hinges 8 which furnishes a visual means for display of bulbs as well as a means for safe and clean protection.

50 Between the paddles 2 and 10 and surmounted on the shaft 6 are spacers 5 and 9 of variable thickness which are in turn straddled over an immovable key strip 3 and upon which the novelty of the invention depends, is the manner in which the paddles which swing on the shaft 6 as an axis other

than the one selected to be moved are kept in an immovable position, and provides as a consequence of the different thicknesses a means to accommodate the storing of various sized bulbs.

Beginning at the top of the cabinet with a preferred number of paddles as shown though not essential are eight paddles containing twenty one holes each as receptacles for small bulbs. The spacer here is of a lesser thickness than the remainder shown in the cabinet which only have, say, ten holes and which contain bulbs of larger diameter as well as increased height.

From the foregoing description, it is thought to be obvious that a light bulb cabinet constructed in accordance with my invention is of extremely simpler and comparative inexpensive nature and is particularly well adapted for use by reason of the convenience and facility with which it may be assembled, and it will also be obvious that my invention is susceptible of some changes and modification without material departure from the scope of the appended claims and for this reason I do not wish to be understood as limiting myself to the precise arrangement and formation of the several parts herein shown in carrying out my invention in practice.

I claim—

1. A container for electric lamp bulbs comprising a cabinet, a vertically disposed shaft arranged therein, a series of shelves pivotally mounted on said shaft and arranged to swing in horizontal planes, each shelf being provided with a series of perforations adapted to receive electric lamp bulbs, spacers mounted on the shaft and disposed between the corresponding end portions of the perforated shelves and a key strip fixedly positioned within the cabinet and engaging all of the spacers to lock same against rotary movement.

2. A container for electric lamp bulbs comprising a cabinet, a shaft vertically arranged in said cabinet at a point adjacent to the front thereof and near its transverse center, two series of shelves pivotally mounted on said shaft and normally positioned between said shaft and the side walls of the cabinet, said shelves being perforated for the reception of electric lamp bulbs, spacers arranged on said shaft and interposed between the inner ends of the shelves, said spacers projecting toward the rear wall

of the cabinet and means secured to the cabinet and engaging the rear ends of all of said spacers for holding same against rotary movement.

5. 3. A container for electric lamp bulbs comprising a cabinet, a shaft vertically arranged in said cabinet at a point adjacent to the front thereof and near its transverse center, two series of shelves pivotally mounted on said shaft and normally positioned between said shaft and the side walls of the cabinet, said shelves being perforated for the reception 30 of electric lamp bulbs, spacers arranged on said shaft and interposed between the inner ends of the shelves, said spacers projecting toward the rear wall of the cabinet and the rear ends of which spacers engage a fixed part of the cabinet so that they are held against rotary movement.
10. 4. A container for electric lamp bulbs comprising a cabinet, a shaft vertically arranged 35 in said cabinet at a point adjacent to the front
15. 5. 3. A container for electric lamp bulbs comprising a cabinet, a shaft vertically arranged in said cabinet at a point adjacent to the front
20. 5. 4. A container for electric lamp bulbs comprising a cabinet, a shaft vertically arranged 40 in said cabinet at a point adjacent to the front
25. 5. 5. A container for electric lamp bulbs comprising a cabinet, a shaft vertically arranged 45 in said cabinet at a point adjacent to the front

thereof and near its transverse center, two series of shelves pivotally mounted on said shaft and normally positioned between said shaft and the side walls of the cabinet, said shelves being perforated for the reception 30 of electric lamp bulbs, spacers arranged on said shaft and interposed between the inner ends of the shelves, said spacers projecting toward the rear wall of the cabinet and the rear ends of which spacers engage a fixed part of the cabinet so that they are held against rotary movement.

5. A container for electric lamp bulbs comprising a cabinet, a vertically disposed shaft arranged within said cabinet near the 40 center thereof, lamp bulb carrying shelves pivotally mounted on said shaft and adapted to swing in horizontal planes, spacers arranged on said shaft and positioned above and below the inner end of each shelf and 45 fixed means within the cabinet for engaging all of the spacers to hold the same against rotary movement.

In testimony whereof I affix my signature.
CLARENCE BRADEN GREENSTREET.
